UNITED STATES PATENT OFFICE.

JOHN B. BAXTER, OF TROY, NEW YORK, ASSIGNOR TO COVERT MANUFACTURING CO.,
OF TROY, NEW YORK, A CORPORATION OF NEW YORK.

HARNESS-TRACE.

1,137,692.

Specification of Letters Patent. Patented Apr. 27, 1915.

Application filed January 30, 1915. Serial No. 5,288.

To all whom it may concern:

Be it known that I, JOHN B. BAXTER, a citizen of the United States, residing at Troy, in the county of Rensselaer and State 5 of New York, have invented certain new and useful Improvements in Harness-Traces, of which the following is a specification, reference being had therein to the accompanying drawing.

10 This invention relates to an improved harness trace, and more particularly to what is known as a double rope trace.

For various reasons and purposes it has been found expedient to provide traces that 15 are strong yet cheap and can be readily, economically and quickly replaced to avoid delay or the necessity of mending by sewing or riveting. There are instances, particularly in connection with military usage, 20 where it is imperative to quickly disengage, engage or replace the traces and for this purpose this double trace is designed and especially applicable. There are many other instances where a double trace is expedient 25 and while rope traces have been suggested before, they have been found to have impractical or objectionable features, which this invention overcomes. In these double traces the parts are drawn down to parallelism, the loops at opposite ends generally being attached respectively to the swingletree and harness in connection with a trace or heel chain or as trace lengtheners.

It is known that a trace is subjected to 30 hard usage, and realizing the additional wear and destructive abrasion caused by the whipping of two parallel courses together with the consequent destruction of the strands, the present invention is designed so as to eliminate this objectionable feature by providing means for maintaining the spliced ends of the endless band or loop in close association with the adjacent course or part of the rope and thereby preventing the heavier spliced parts from whipping around or against and destroying the adjacent course of the double trace.

45 In the accompanying drawing is shown a preferred embodiment of the invention and a modified form, but it is to be understood that the specific forms of invention shown are employed herein for the purposes of illustration and that the general inventive idea is susceptible of being embodied in

various other forms without departing from 55 the nature and principle of the invention.

In the drawing: Figure 1 represents a double trace embodying the invention and showing its application; Fig. 2 is a detail view of the trace showing its slicing connections, loop and "drop ring," Fig. 3 is a section on line 3—3 of Fig. 1, and Fig. 4 illustrates a modified form of the loop and drop ring.

In the drawing the swing-tree end is 65 shown somewhat diagrammatically at A, while the snap or harness ring end is shown at B.

C designates the double rope trace. This trace is made of a single piece of rope having its end parts passed through a loop or ring member D and carried back and secured to the rope body by any convenient means, preferably the metal clamping rings E. By this means a continuous band is 70 formed which constitutes, when in use, a double rope trace. Where the ends of the trace are spliced or united there is manifestly considerably more weight than at other points, and in use this part of the 75 trace has a more pronounced snapping or violent movement toward and from the other part owing to its weight and its associated members. To unite the adjacent parts of the two courses of the trace loosely 80 and yet to maintain free relative lateral positions, a drop ring F is attached to the loop D and this ring is of sufficient diameter to permit easy passage of the other or adjacent part of the double rope trace. This ring F 85 may be attached to the loop D in various ways. In Fig. 1 it is shown as a ring passing through the loop, and in Fig. 4 it is shown as an integral part or casting with one of the side bars of the loop, as shown, 90 wherein the loop D' is represented as a ring member and one part of the casting, while the drop ring D² is represented as another part of the casting. Of course various modifications can be made of this loop and 95 drop ring construction.

In use the splice with the loop and drop ring are generally and designedly by preference, located midway the length of the trace. In this position the two parts of 105 the rope are held in proper position against becoming entangled or side whipping, one against the other, and there is the requisite

freedom of movement between the two members for equalizing strains on the two parallel members of the trace and the parts are generally maintained in their proper relative position.

It is to be understood that where the term "loop" is employed in this specification, it is intended to comprehend and include other structures, such as rings or devices which are analogous, or serve the purpose of a loop. It is also to be understood that the term "rope" is used to include analogous bands or members.

The invention has been found highly beneficial and adds materially to the life of the trace.

Other advantages accrue from the use of the invention as will be obvious to those skilled in the art.

Having thus described the invention, what is claimed as new and desired to be secured by Letters Patent is:

1. A doubled rope trace for harness comprising a single piece of rope having a loop

through which the ends of the rope are passed, means for securing the ends of the rope in the loop, and a drop ring member carried by the loop and through which the adjacent part of the rope trace passes.

2. In a rope trace, the combination with a rope, of a loop member to which the ends of the rope are attached, and a laterally extending drop member on the loop member through which a part of the rope freely passes.

3. A rope trace composed of parallel parts and having a ring member intermediate its ends, and an associated member directly connected to the ring member for retaining the two parallel parts of the trace against relative lateral whipping movement.

In testimony whereof I hereunto affix my signature in the presence of two witnesses.

JOHN B. BAXTER.
